RAILWAY TRACK CIRCUITS

Harold G. Witmer, Pittsburgh, Pa., assignor to
The Union Switch & Signal Company, Swiss-
vale, Pa., a corporation of Pennsylvania

Application February 21, 1935, Serial No. 7,602

11 Claims. (Cl. 246—34)

My invention relates in general to railway track circuits; and more particularly to track circuits wherein a minimum reduction of current flow in the track circuit employed to pick up the track relay will be required to effect the release of the track relay.

I am aware that various methods of increasing the release sensitivity of a track circuit have heretofore been proposed, but most of these with 10 which I am familiar approach the problem by, in one manner or another, changing the release sensitivity of the track relay itself, so that a less effective shunt across the track rails will shunt sufficient current from the track relay to effect its 15 release than would otherwise be required.

One of the main features of my invention has to do with the provision of means sensitive to a slight reduction in current flow in that portion of the track circuit which feeds the track relay, to open 20 the circuit of the track relay, or in another manner remove all operating current therefrom to effect its release.

I will describe various forms of the track circuit embodying my invention, and will then point out 25 the novel features thereof in claims.

In the accompanying drawing, Fig. 1 is a dia- 30 grammatic view of one form of apparatus embodying my invention; while Figs. 2-6 are dia- grammatic views of other forms of apparatus, 35 each of which also embodies my invention.

Similar reference characters refer to similar parts in each of the several views.

Referring to Fig. 1, the reference characters 4 and 5 designate the rails of a section A—B of rail- 35 way track, separated from adjoining sections by 35 way track, separated from adjoining sections by insulators 6 in the usual manner, and over which traffic normally moves in the direction indicated by the arrow.

Alternating current is fed to the rails 4 and 5 of 40 the section, at the exit end thereof, from the sec- 45 ondary S1 of a suitable transformer T1 via a cur- rent limiting reactor 7. At the entrance end of the track section, the primary winding P2 of a 45 step-up transformer T2 is bridged across the track rails 4 and 5. The secondary winding S2 of a transformer T2 is included in a loop circuit includ- 50 ing a fuse F, the primary winding P3 of a step-down transformer T3, and a Geissler or glow discharge tube GDT of the type having two like “plain” electrodes which allow passage of current 55 in both directions. The secondary winding S3 of transformer T3 is connected to the terminals of the track relay TR, through a rectifier BR.

The current normally supplied to the rails 4 and 55 5 by transformer T1 is received by the primary

winding P2 of transformer T2, which induces just enough voltage in the described loop circuit to break down the glow discharge tube GDT and permit current to flow through it when the track ballast leakage is greatest. The resulting current 5 flow through the primary winding P3 of step- down transformer T3 induces a current flow in its secondary winding S3, causing the track relay TR to be energized through the rectifier BR.

The character of the glow discharge tube GDT 10 is such that the voltage required to break down the tube is very nearly the same as that at which the tube cuts off. Therefore, in response to a drop in potential—very small compared to that required to drop a track relay directly energized 15 over the track circuit by shunting current from it—the tube will cut off and cease feeding current to the track relay.

The primary winding P3 of transformer T3 may be designed to have sufficient impedance to prop- 20 erly limit the flow of current through the tube when the tube breaks down; and fuse F or a lamp is employed as a means for opening the tube cir- 25 cuit in case the elements of the tube become short-circuited due to physical breakage of the tube. As most of the voltage drop is normally across the elements of the tube, if these elements should become short-circuited, sufficient current will flow to blow the fuse or burn out the filament 30 of the lamp, thus opening the circuit.

For the purposes of explaining the operation of the track circuit of Fig. 1, I will assume that the tube GDT breaks down on any potential over 50 35 volts, and will cut off on potentials under 50 volts. The track circuit will accordingly be adjusted to 35 feed slightly more than 50 volts to the secondary S2 of the transformer T2 and accordingly across the terminals of the tube GDT under greatest ballast leakage conditions. The tube then breaks down and enables the transformer T3 and recti- 40 fier BR to deliver normal operating current to the track relay TR.

When the track section becomes occupied any shunt on the track which will reduce the potential in the loop circuit including the tube GDT 45 below 50 volts, say to 49 volts, will cause the tube to automatically cut off the energy supply to transformer T3 and accordingly to the track relay, as the tube will not conduct current unless the potential in its circuit is over 50 volts. The 50 armature of the track relay will accordingly be released as a result of the complete removal of operating current from its winding, rather than as in the formerly referred to arrangements, wherein release of the relay armature depends on 55

a reduction of current flow below that required to hold its armature in the operated position.

In Fig. 2, I have shown the track relay TR as an alternating current relay and therefore connected in series with the secondary of the transformer T2 and the tube GDT. With this arrangement, the operation will be essentially the same as that described for Fig. 1. Explaining the operation more specifically, a slight drop in potential across the terminals of the primary winding P2 of the transformer T2 will drop the potential across the secondary winding S2 of this transformer to a point sufficiently below the break down value of the tube GDT to cause it to cut off. When the tube cuts off, the supply of operating current to the track relay is interrupted, causing it to immediately release its armature.

In Fig. 3, I have shown a track relay directly included in the secondary portion of the track circuit, as in Fig. 2, but instead of employing a glow discharge tube of the type having two like "plain" electrodes, allowing passage of current in both directions, I have employed a glow discharge tube GDRT of the rectifier type employing one "plain" and one "point" type of electrode, thereby enabling me to employ a direct current track relay instead of one of the alternating current type. The break down and cut off operating characteristics of the tube GDRT are the same as of the type employed in Figs. 1 and 2.

In Fig. 4, I have shown the tube GDRT connected in multiple with the track relay. With the secondary portion of the track circuit arranged in this manner and with a normal current flow through the primary circuit, the tube breaks down and during alternate half-cycles of the alternating current, shunts current away from the track relay, while during the remaining half-cycles the current will be flowing through the track relay, so that the relay is picked up and held up by those unidirectional pulses of current not shunted by the tube. The track relay is, in this form of the invention, necessarily so designed that it will not pick up nor be held up by unrectified alternating current, so that when the tube cuts off in response to a reduction of the alternating current potential, the relay will promptly release its armature. I have shown a resistor 8 connected in series with the tube GDRT to limit the current flow through it when the tube breaks down. It will be understood, however, that, with any of the arrangements shown, the impedance of the rails, leakage between the rails, and the reactor 7 will tend to limit the flow of current at such time.

In Fig. 5, I have shown an arrangement similar to that shown in Fig. 3 except that two rectifier type tubes GDRT are employed. It will be apparent that with this arrangement, when the tubes break down, they will function as a full wave rectifier, and therefore current will flow through the relay in the same direction for each half-cycle of the alternating current, and will cut off the current supply to the track relay when the tubes cut off in response to a reduction in potential in its operating circuit.

It will be apparent that the results obtained in Figs. 3, 4 and 5, by employment of a glow discharge tube of the rectifier type, may also be obtained by employing a glow discharge tube such as GDT in series with a dry disc rectifier.

Fig. 6 shows the latter arrangement in a form which is equivalent to the arrangement shown in

Fig. 3, wherein a rectifier R is connected in series with the glow discharge tube GDT.

In concluding the description of my invention, I wish to emphasize that, since the tubes employed by me are of a type which will not allow any current to pass until the voltage supplied to them has increased to their break down value, after which the current is limited almost entirely by the impedance in series with the circuit, it is evident that in the various forms of my invention the pick-up and release values of the track relays will be practically the same. My invention, therefore, teaches various methods of providing a track circuit having greater sensitivity than can be obtained with a track circuit wherein a standard relay is directly included in the track circuit and has a release which depends on a reduction of the current flow through it, rather than on a positive interruption of the current supplied thereto.

Although I have shown herein only a limited number of variations of my invention, it will be apparent that various changes and modifications may be made therein within the scope of the appended claims without departing from the spirit and scope of my invention.

Having thus described my invention, what I claim is:

1. In combination with a section of railway track, means supplying a potential across the rails of the section at one end thereof, a track relay and a transformer at the other end of the section, a bridge across the rails of said section comprising the primary winding of said transformer, and a glow discharge tube included in circuit with the secondary winding of said transformer responsive to pass operating current through the winding of the track relay when and only when the section is unoccupied and the potential of current supplied to the secondary winding of said transformer is above a predetermined minimum value whereby said track relay will release more positively due to the interruption of the operating current when a train enters said section and the potential across said secondary winding decreases below said predetermined value.

2. In combination with a section of railway track, means supplying a potential across the rails of the section at one end thereof, a track relay and a transformer at the other end of the section, a bridge across the rails of said section comprising the primary winding of said transformer, an operating circuit for said relay including the secondary winding of said transformer, and a device connected in said circuit having the characteristic of opening and closing the circuit through itself in response to slight variations in potential in the operating circuit such as occur when a train enters and leaves the section, respectively, whereby the operating circuit for said track relay will be interrupted to insure the release of said track relay upon the entry of a train into said section.

3. In combination with a section of railway track, means supplying a potential across the rails of the section at one end thereof, a track relay and a transformer at the other end of the section, a bridge across the rails of said section comprising the primary winding of said transformer, an operating circuit for said track relay including the secondary winding of said transformer, means for reducing the potential applied to the primary winding of said transformer when a vehicle enters the section, and means included

in said operating circuit for passing operating current to said track relay when and only when the section is unoccupied and responsive to the decrease in potential when the section becomes occupied to entirely cut off the supply of current to said relay.

4. In combination with a section of railway track, means supplying a potential across the rails of the section at one end thereof, a track relay and a transformer at the other end of the section, a bridge across the rails of said section comprising the primary winding of said transformer, a circuit including a glow discharge tube and the secondary winding of said transformer for supplying operating current to said relay when and only when the section is unoccupied and for completely interrupting the current when the section becomes occupied, and means included in said circuit for preventing said relay receiving current from the secondary winding of said transformer should the elements of said tube become short circuited.

5. In combination with a section of railway track, a transformer having its primary winding connected in bridge of the rails of the section, a track relay for said section, a glow discharge tube connected in series with the secondary winding of said transformer in an otherwise closed circuit and effective when and only when a breakdown potential is received by the secondary winding of said transformer to pass operating current on to the track relay, and means for supplying the track rails of the section with a suitable potential for effecting the discharge or breakdown of said tube when said section is unoccupied, whereby said operating current will be completely interrupted when the section becomes occupied.

6. In combination with a section of railway track, means supplying a potential across the rails of the section at one end thereof, a track relay and a transformer at the other end of the section, a bridge across the rails of said section comprising the primary winding of said transformer, and an operating circuit for said relay including the secondary winding of said transformer and a glow discharge tube, the parts being so proportioned that when a train enters said section the glow discharge tube will cut-off and will interrupt said operating circuit to insure the release of said track relay.

7. In combination with a section of railway track, means supplying a potential across the rails of the section at one end thereof, a track relay and a transformer at the other end of the section, a bridge across the rails of said section comprising the primary winding of said transformer; a control circuit for said relay including the secondary winding of said transformer, the primary winding of a second trans-

former and a glow discharge tube; and an operating circuit for said relay including a rectifier receiving current from the secondary winding of said second transformer.

8. In combination with a section of railway track, means supplying a potential across the rails of the section at one end thereof, a track relay and a transformer at the other end of the section, a bridge across the rails of said section comprising the primary winding of said transformer; a circuit including the secondary winding of said transformer receiving current supplied to the primary thereof and including a glow discharge tube through which current of the potential supplied to the rails of said section normally flows, and the primary winding of a second transformer; a circuit including the secondary winding of the second transformer and the input side of a rectifier, and a track relay operated from current supplied by the rectifier so long as the potential across the secondary winding of the first transformer is sufficient to prevent the cut off of said glow discharge tube.

9. In combination with a section of railway track, means supplying a given potential across the rails of the section at one end thereof, a track relay and a transformer at the other end of the section, a bridge across the rails of said section comprising the primary winding of said transformer, and an operating circuit for said relay comprising the secondary winding of said transformer shunted by a glow discharge tube of the rectifier type.

10. In combination with a section of railway track, means supplying a given potential across the rails of the section at one end thereof, a track relay and a transformer at the other end of the section, a bridge across the rails of said section comprising the primary winding of said transformer, and an operating circuit for said track relay alternately including one and then the other of two glow discharge tubes connected in series with opposite halves of the secondary winding of said transformer.

11. In combination with a section of railway track, means supplying a potential across the rails of the section at one part thereof, a track relay and an inductive coupling, a bridge across the rails at another part of said section comprising one portion of said inductive coupling, and means including a glow discharge tube and the other portion of said inductive coupling connected in series for supplying operating current to said relay, the parts being so proportioned that when a train enters said section the glow discharge tube will cut-off and will interrupt the operating current to insure the release of said track relay.

HAROLD G. WITMER.
